UNITED STATES PATENT OFFICE.

HAROLD W. HOLLENBECK, OF KIRKLAND, WASHINGTON, ASSIGNOR TO DURABLE MAT COMPANY, OF SEATTLE, WASHINGTON, A CORPORATION OF WASHINGTON.

LINK-MAT-ASSEMBLING MACHINE.

Application filed January 23, 1928. Serial No. 248,869.

My invention relates to apparatus which is used to assemble links upon connecting or pivot wires to form mats. Its object is to facilitate such work and to reduce its cost 5 over hand methods.

My invention consists essentially of means for holding in proper spaced relation the wires upon which the links are assembled, and means whereby the links for a row may 10 be assembled upon a carrier or threading bar and then by suitable movement of such bar, be all placed upon the wires at one time. My invention comprises the said holding and threading bar and the manner of controlling 15 and operating it.

The accompanying illustrations illustrate my invention embodied in the form which is now employed by me.

Figure 1 is a plan view of the machine 20 with certain parts broken away or removed to better show parts below.

Figure 2 is a side view in which parts of the mechanisms employed in placing the links are in section.

Figure 3 is a front elevation of a portion 25 of the width of the machine showing the important working parts.

Figure 4 is a detail assembly of certain of the operating parts, the plane of view being 30 vertical and extending from front to rear.

Figure 5 is a plan view of certain parts employed in reciprocating the link-assembling and placing bar.

Figure 6 is a vertical section of the link- 35 placing mechanism, similar to that of Figure 4, but with the parts in different position.

Figure 7 is a cross-sectional elevation of a hammer mechanism which acts upon the back ends of the pintle wires to thereby assist 40 in the relative backward movement of the links upon these wires.

The machine illustrated in the accompanying drawings and herein described has been 45 specifically designed for assembling links cut from old rubber tires upon pivot or pintle wires to make mats. It will be herein specifically described as employed for that purpose, although it is to be understood that I am aware that it may be employed in doing 50 analogous work upon other materials, and that I claim the same for any use to which it may be put. The specific description of the invention hereinafter given is intended to be merely illustrative of the principles employed and the manner of use.

The operating parts of my machine are shown as mounted in suitable relation upon a frame 1, which may be made of any material, shape and character of construction found suitable. Means are employed for 60 holding the wires 10, upon which the links 11 are assembled, in proper parallel spaced relation. Preferably the wires are each of elongated U-shape, the stems or sides, thereof being slightly longer than the width of 65 the mat which is being made.

These rods or wires are held in proper spaced and parallel relation by a bar 12, which contains cross channels into which the bend of the wires drop, and by a suitable 70 holding and spacing bar 13 which is transversely grooved to accommodate the wires and engages them near their ends. The wires are thus held in exact position in a horizontal plane with their free ends projecting to receive thereon the links.

A bar 2 is provided with suitable means for positioning and holding thereon in proper spaced relation a sufficient number of links to form one row across the mat. This relation corresponds with the spacing of the wires 10. The construction chosen for illustration has recesses 20 in the face of the bar of a size and shape to each accommodate a link. I have also shown these recesses as 85 communicating with the outer edge of the bar by a throat 21 of less width than the length of a link.

It is evident that if a row of links be placed upon this holding or assembling bar, 90 positioned to exactly register with the positioning of the wires 11, and the bar be then presented to and advanced upon the wires, the links carried thereon will all be threaded upon the wires at one time. It is, of course, 95 assumed that the links have suitable perforations at each end adapted to receive said wires.

For the purpose of convenience in placing the links in the recesses of the holding or assembling bar, this is at that time in horizontal position with its recessed face up, as is shown in Figures 3 and 4, or inclined as in Figure 6. This bar is mounted upon a frame 3 which is carried upon the laterally offset 100 pivot rod 30, these parts being positioned and proportioned so that when rocked clockwise, as shown in Figure 4, the holes in the links will exactly register with the ends of the wires 10. The bar 2 has holes for the 110

passage of the wires and the movement of bar 2 is sufficient to advance the links a short distance upon the wires.

The placing of each row of links will further advance the previously placed links. In a link mat, the links of each row are positioned opposite the spaces of the next adjacent rows. It is, therefore, necessary to shift the holding or assembling bar 2 lengthwise between each link-threading movement a distance equal to the pitch length of the links. Therefore, the bar 2 has been mounted in guideways 31 carried by the frame 3. The means for causing this intermittent reciprocal motion will be later described.

The pivot rod 30 is mounted to have a horizontal movement toward and from the machine as by carrying it upon the upper end of a frame 35, pivoted at 36. Upon the frame 3 or 35, concentric with and preferably upon the rod 30, is mounted a pulley or wheel 37, to which is secured one end of a chain 38, or other equivalent flexible connecting means. This chain passes over a guide wheel, pulley or gear 39, and is connected with a pin 40 carried by a crank arm 4, fixed upon a shaft 41. These parts should be so proportioned in size that the take up or release of the chain caused by one turn of the shaft 41 will cause the required angular swing of the frame 3 and the additional horizontal movement of frames 3 and 35 which advances the links upon the wires. While the turning of crank arm 4 is in one direction only and through a complete circle each time, the turning movement of frame 3 is 90° or less and is followed by a reciprocating movement. Frames 3 and 35 are provided with surfaces engaging as at 32 to limit the swing of frame 3. A spring 42 returns frame 35 to its normal position.

The shaft 41 is intermittently driven from a clutch device shown at 5, as through a chain 50 and suitable gears. Associated with the clutch 5 is a gear 51 continuously driven by a worm 52 turned by the motor 53. The clutch is controlled by an arm 54 and is normally disconnected, so that the parts driven therethrough are stationary. A link 55 connects the clutch-controlling arm 54 with a trip arm 56, pivoted upon a fulcrum bracket 57, which latter is pivoted at 58 (see Figure 3) and is controlled by a rod 47 which extends to a position where it is easily accessible to the operator. The bar or lever 56 has a side extending ear 59 normally positioned to be in the path of swing of the pin 40 carried by the crank arm 4. It also has a curved edge 48 which is engaged by the pin 40 to raise this end of the lever 56 at the completion of the turning movement of arm 4. This movement of lever 56 disengages the clutch.

A shaft 44 is turned through gears 43 from shaft 41, and at the front of the machine

carries an arm 45 having a crank pin 46 which enters a slot 60 in a lever 6, pivoted at its lower end 65. The ratio of gears 43 is two to one, so that the pin 46 makes only a half circle swing at each operation of the clutch.

The upper end of lever 6 is used to reciprocate the link-holding and assembling bar 2. It is immediately connected with a mechanism shown in Figure 5. Its forked upper end 61 embraces a rod 62 upon which freely slide washers 63 and about which are the helical springs 64. A bar 7 has ears 70 located outside springs 64, and through which the rod 62 freely passes. Bar 7 has a block 71 secured thereto and mounted on guides 72. A locking dog 73 is normally held by the spring 74 in one or the other of two locking recesses 75 in bars 72. Block 71 has a transverse slot 77 into which enters the rib or flange 24 carried by the swinging frame 3. A pin 76 will depress and disengage the locking dog 73 when depressed by the flange 24. In this condition the block 71 is free to move upon its guide rods 75, and as the movement of the lever 6 has preceded the release of the block 71, one of the springs 64 is compressed and throws the bar 7 and the attached block 71 over to its other position, where the locking dog 73 engages the other notch 75. In doing this it carries with it the flange or lug 24 and the link-holding and assembling bar 2. The reciprocation of the bar 2 occurs when it is released by action of the flange 24 upon the pin 76 and the locking dog 73, which is upon completion of the return movement of the bar-carrying frame, 3.

I have shown a series of spring fingers 8 carried by a cross bar 80 and by their free end pressing down upon the links 11 which have just been placed upon the wires. These serve to hold the wires down at their proper level and to prevent withdrawal of a link. These parts, and also the plate 81 which is beneath the links are mounted to yield backwardly by the pressure of the link-holding bar 2. Guide rods 82 are fixed to these parts and reciprocate in guides carried by the frame. Springs 83 return all these parts outwardly when pressure is removed therefrom.

I have found that the backward movement of the links 11 upon the pivot or pintle rods 10 will be facilitated by giving these rods a sharp rap at their back ends at the time the link-placing bar 2 is being moved back. I have therefore provided means for doing this, as follows:

Journalled at the rear of the machine is a shaft 9 upon which are loosely mounted a number of hammer arms 92 corresponding with the number of the rods 10 upon which the links are strung. Fixed to shaft 9 are a like number of collars 90, each carrying

a spring arm 91 which are also connected with their respective hammer arms 92 to actuate them.

Shaft 9 has an arm or arms 93 fixed there-
5 to by which it may be rocked to withdraw
the hammer arms and a spring or springs
94 for returning the hammer arms so that
they will strike a sharp blow upon the rods
10. Arm 93 has a finger 96 pivoted thereon
10 and prevented by stop lug 102 from swing-
ing in one direction while free to swing in
the other direction. A rod 97 mounted to
reciprocate in guides, carries a pin 98 posi-
15 tioned to engage the projecting tip of finger
96, thereby to swing the arm 93 when moved
in one direction. The movement of rod 97
is enough to permit release of the finger,
whereupon spring 94 causes a quick return
of the hammers. A sharp blow of this char-
acter is highly efficient in overcoming the
20 frictional resistance between the wires 10
and the links, thus aiding the backward
movement of the links, particularly after
the wires become nearly filled.

25 The reciprocation of rods 97 may be se-
cured by various means. That shown is
from an arm 99 carried by a shaft 102 on
which is a gear 100 actuated by engagement
30 with the intermittently reciprocated chain
38.

What I claim as my invention is:

1. A means for placing links upon pintle
wires comprising means for holding the
wires with their ends in proper spaced re-
35 lation, a holder for a plurality of links
securing a conforming endwise spacing
thereof, and means for moving said holder
to simultaneously place said plurality of
lengths upon said wires.
40 2. A means for placing links upon pintle
wires comprising means for holding the
wires with their ends in proper spaced re-
lation, a holder for a plurality of links
securing a conforming spacing thereof, and
45 means for moving said holder to place the
links held thereon upon said wires, and
means for lengthwise shifting said holder to
alternately position the links of successive
rows.

50 3. A means for placing links upon pintle
wires comprising means for holding the
wires with their ends in proper spaced re-
lation, a holder for a plurality of links
securing a conforming spacing thereof, and
55 means for moving said holder to place the
links held thereon upon said wires, and
yielding presser members bearing upon the
links last placed upon the wires.

60 4. A means for placing links upon wires
to form a mat comprising means for holding
the wires with their ends properly spaced,
a holder bar having a plurality of link re-
ceiving and positioning means and means
65 for swinging said bar to place the links upon
the wires.

5. A means for assembling links upon
wires to form a mat comprising means for
holding the wires in properly spaced relation,
a link positioning and transferring bar
having link positioning and holding means
70 and means for swinging it about an axis
laterally offset therefrom and means for
lengthwise shifting said bar an amount corre-
sponding with the pitch length of the links.

6. A means for placing links upon wires
75 to form a mat comprising means for holding
the wires with their ends properly spaced, a
holder bar having link receiving and posi-
tioning means, a frame upon which the hold-
er bar is mounted for lengthwise movement,
80 said frame being mounted to swing upon
an axis laterally, offset from said bar, means
for swinging said frame and means for re-
ciprocating the holder bar alternately in
opposite directions.
85

7. A means for assembling links upon
wires to form a mat comprising means for
holding the wires in properly positioned re-
lation, a holder bar having means for posi-
90 tioning a row of links to conform with that
occupied in the mat, means for advancing
said holder bar to place its row of links upon
the wires and to slide them along the wires.

8. A link-mat assembling machine com-
prising means for holding the wires in prop-
erly spaced relation, a holder bar having
means for holding a row of links in spaced
relation corresponding with that of the
wires, a frame upon which the holder bar is
95 pivotally supported by a laterally offset axis
to swing towards and from the ends of the
wires to properly register the links with the
receiving wires, means for first swinging
said holder bar to present the links to the
wires and for then swinging the main frame
100 to thereby force the links back upon the
wires.
105

9. A link-mat assembling machine com-
prising means for holding the wires in prop-
erly spaced relation, a holder bar having
means for holding a row of links in spaced
relation corresponding with that of the
wires, a frame upon which the holder bar is
110 pivotally supported by a laterally offset axis
to swing towards and from the ends of the
wires to properly register the links with the
receiving wires, and means for operating
said parts containing a connecting member
115 acting through the holder bar to first swing
the said bar into position to present the links
to the wires and then to swing the frame to
thereby force the links upon the wires.
120

10. A link mat assembling machine com-
prising means for holding the link-connect-
ing wires in proper spaced relation, a holder
bar for the links, two frames upon one of
which said bar is mounted, the latter frame
being pivoted upon the other and said other
frame being pivoted, said pivots being posi-
125 tioned to permit swinging of each frame
130

towards the receiving ends of the connecting wires, and actuating means connected to the holding bar frame and acting to first swing said frame to present links placed thereon to the wires and then to swing both the frames to advance the links upon the wires.

11. In a link-mat assembling machine, means for holding the link-connecting wires in proper spaced relation, a link holding bar 10 provided with means for proper positioning a row of links, a frame upon which said bar is mounted for lengthwise reciprocation, a second frame mounted for reciprocation toward and from the link-connecting wires 15 and upon which the first frame is pivoted to similarly swing, means connected with the first frame to swing both frames in succession toward and from the wires, and means for lengthwise movement of the 20 link-holding bar a link length after each swinging movement thereof, said movements being alternately in opposite direction.

12. In a link-mat assembling machine, a link holding and placing bar provided with 25 means for holding a row of links in end-to-end relation and in proper spacing for insertion upon the connecting wires, and means for moving said bar to thread the links upon said wires.

30 13. In a link-mat assembling machine, a link holding and placing bar provided with means for holding a row of links in proper spacing for insertion upon the connecting wires, and means for moving said bar to thread the links upon said wires, and means for lengthwise shifting said bar one-link-length and alternately in opposite directions 35 between the placing of each row of links upon the wires.

40 14. In a link-mat assembling machine, a bar having recesses for receiving and positioning a row of links and holes for passing the link-holding wires of a mat, and means for moving said bar to place the links upon 45 the wires.

45 15. In a link-mat assembling machine, means for holding the link-connecting wires of the mat, a link assembling bar, a holder for said bar mounted to swing towards and 50 from the ends of the said wires and to permit lengthwise reciprocation of the bar thereon, locking means normally holding said bar against reciprocation, means for oscillating the holder for said bar means 55 for reciprocating said bar in its holder, and means for releasing the bar reciprocating means at and by the return movement of the bar holder.

60 16. In a link-mat assembling machine, means for holding the link-connecting wires

of the mat, a link assembling bar, a holder for said bar mounted to swing towards and from the ends of the said wires and to permit lengthwise reciprocation of the bar thereon, and means for reciprocating said 65 bar at the end of the swinging movement of the holder.

17. The method of forming a link mat which consists in securing the pintle rods in properly spaced relation, assembling a 70 row of links in proper end-to-end relation and applying a single row of links to the rods at a time.

18. The method of forming a link mat which consists in securing the pintle rods in properly spaced relation, assembling a 75 row of links in proper relation and applying a single row of links to the rods at a time, successive rows of links being lengthwise offset by an amount equal to the pitch 80 length of the links.

19. The method of forming a link mat which consists in securing the pintle rods in properly spaced relation, assembling a 85 row of links in proper relation and applying a single row of links to the rods at a time, and pushing the previously assembled links back upon the rods by the newly placed links until the mat is completed.

20. In a link mat assembling machine, 90 means for holding the threading wires in properly spaced relation, means for presenting and placing the links upon said wires and means for rapping the back ends of said wires at the time of placing the links thereon.

21. In a link mat assembling machine, means for holding the threading wires in properly spaced relation, means for presenting and placing the links upon said 100 wires, hammers pivoted to engage the back ends of said wires when swung, and means for so swinging the hammers to rap the wires at the time of placing the links upon the wires.

105 22. In a link mat assembling machine, means for holding the threading wires in properly spaced relation, means for presenting and placing the links upon said wires, a series of hammers pivoted to be swung into 110 engagement with the back ends of the wires, springs acting to normally urge the hammers towards said wires, and means acting to withdraw the hammers and to release them to strike the wires at the time of placing the 115 links thereon.

Signed at Seattle, Washington this 4th day of January, 1928.

HAROLD W. HOLLENBECK.
